UNITED STATES PATENT OFFICE

AUGUSTO DINA, OF JERSEY CITY, NEW JERSEY, ASSIGNOR TO INTERNATIONAL PROJECTOR CORPORATION, OF NEW YORK, N. Y., A CORPORATION OF DELAWARE

SEMITAUTOMATIC ADJUSTABLE SUPPORT FOR PICTURE-PROJECTING MACHINES

Application filed May 31, 1928. Serial No. 281,871.

This invention relates to picture projection apparatus, and more particularly to an adjustable support therefor to permit the apparatus to be operated in two positions, as for example, for motion pictures and for still pictures.

Motion picture projection machines are frequently located at the rear of a theatre in such position that the line of projection must extend forwardly and be inclined to the horizontal by a substantial angle. When the machine is to be used for the projection of still pictures the lamp house is moved laterally to a suitable position for projecting the light through the still plate instead of through the motion picture projection head. In so moving the lamp house it is essential to maintain the line of projection in parallelism in order to avoid the necessity of further adjusting the machine and focusing the images upon the screen.

This invention provides a new and improved support whereby the lateral movement of the lamp house is facilitated and whereby the assembly is secured with extreme rigidity in either of its operative positions.

The invention further provides mechanism for relieving the lamp house support of a portion of the weight of the bracing frame during the adjustment whereby the frame is prevented from binding and otherwise interfering with the movement. By reason of this type of support there is provided a semi-automatic adjustable support for projection machines.

This is accomplished by providing a pair of springs in a position to cooperate with the bracing frame and causing the springs to support the weight of said frame when the parts are unclamped for purposes of adjustment. In operative position the parts are securely clamped together whereby vibrations of the machine are prevented.

The invention also consists in certain new and original features of construction and combinations of parts hereinafter set forth and claimed.

Although the novel features which are believed to be characteristic of this invention will be particularly pointed out in the claims

appended hereto, the invention itself, as to its objects and advantages, the mode of its operation and the manner of its organization may be better understood by referring to the following description taken in connection with the accompanying drawings forming a part thereof, in which

Like reference characters denote like parts in the several figures of the drawings.

In the following description and in the claims parts will be identified by specific names for convenience, but they are intended to be as generic in their application to similar parts as the art will permit.

Referring more particularly to the drawings, there is shown in Fig. 1, a motion picture projection apparatus comprising a base member 15 having suitable supporting feet 16 and adapted to carry the various parts of the apparatus. Conduit 17 is passed through said base into a connection box 18 from which the electrical connections to the various parts of the apparatus are taken. A foot switch 19

is supported by the base as the central portion thereof and includes a plunger 20 which is adapted to be pressed downwardly by the foot of the operator to connect and disconnect motor 21 from the current supply line.

Pedestal 22 is secured to the forward part of base 15 in any suitable manner and operates as a support for the various pieces of apparatus. Pedestal lever 23 is pivotally secured to the top of pedestal 22 as by bolt 24 and is provided with a forward extension 25 by means of which the projection head 26, upper film magazine 27 and lower film magazine 28 are supported. Lever 23 is provided rearwardly with vertically aligned bearings 29 to which web 30 is pivotally secured. Lamp house base 31 is pivotally secured as by bearing 32 to web 30 and carries lamp house 33 of any well known construction. A guide rod 30a is pivotally mounted in bearings 29a of lever 23 and is secured to lamp house base 31 for maintaining the same in parallelism during movement thereof.

Adjusting screw 34 is rigidly supported in bracket 35 which is secured to pedestal 22 in any desired manner as by bolts 36. Yoke 37 which is rigidly secured to pedestal lever 23 contacts with collar 38 and determines the angle of projection of the machine. Collar 38 is threaded on screw 34 and may be operated by hand wheel 39.

Lamp house supporting bracket 40 having tubular bearing members 41 is secured to lamp house base 31 and is adapted to slide longitudinally of rod 42 forming a part of the rear supporting frame of the machine. The rear supporting frame comprises a pair of vertical rods 43 secured to yoke 44 which in turn carries rod 42. Vertical rods 43 are adapted to slide in tubular members 45 which are in turn carried by yoke 46, said yoke being pivotally secured to the rear end of base 15 as by bearings 47. Suitable locking means controlled by lever 48 may be employed for preventing relative movement of rods 43 and bearings 45 when desired. Switch 50 may be carried by cross brackets 51 which are supported from rods 43.

The details of construction of the lamp house supporting means and of the rear bracing frame are shown more in detail in a co-pending application of Augusto Dina, Serial No. 257,831, filed February 29, 1928. Only so much thereof has been disclosed in the present specification as is necessary to an understanding of the invention thereof.

Lamp house supporting bracket 40, as shown more in detail in Figs. 8, 9 and 10, comprises a pair of tubular members 41 adapted to slide on rod 42 and a split member 52 having its two sides suitably threaded to receive the clamping screw 53 (Fig. 2) whereby the bracket may be securely locked in any desired position on rod 42.

In the operation of the above described ap-

paratus pivotal adjustment about bolt 24 is obtained by loosening clamping means 48 and advancing collar 38 on screw 34 by means of hand wheel 39. Pedestal lever 23 is thus pivoted about bolt 24 and the lamp house 70 and projection head correspondingly moved. The lamp house may be moved transversely of the machine by sliding bearings 41 along rod 42, handle 54 being attached to an extension of web 30 for this purpose. 75

When the lamp house is so moved, and particularly if the machine is so adjusted as to provide a downward inclination of the line of projection, the rear supporting bracket is pivoted about bearing 47 and caused to undergo a change of length. If the movement of the lamp house causes an increase in elevation thereof the supporting frame is raised by bearings 41 and rod 42. A sufficient force must, therefore, be exerted upon handle 54 to raise the lamp house and to carry the weight of the rear supporting frame. Furthermore, assuming the lamp house to be in position at the left of rod 42 as viewed in Fig. 2, the entire weight of the rear supporting frame is carried from bearings 41 which are considerably off center with respect to the center of gravity of the frame. A moment is accordingly produced which tends to tighten rod 42 in bearings 41 and render 85 sliding movement thereof more difficult. 90

In accordance with the present invention, the lateral shifting of the lamp house is facilitated by including a pair of helical springs 55 on rods 43 in such manner that they may support the weight of the rear frame and if desired a portion of the weight of the lamp house. Springs 55 are secured between bearing members 45 and spring retaining collars 56. 100

Collars 56, as shown more in detail in Figs. 5, 6 and 7 comprise an inner member 57 slidably mounted on rod 43 and provided at its upper end with a split member 58, the two sides of which are threaded to receive clamping screw 59 by means of which the collar may be secured to rod 43 in any desired position. An outer member 60 is threaded upon member 57 and contacts with a suitable washer 61 which is adapted to engage the upper end of spring 55. The surface of member 60 may be suitably knurled to permit the same to be readily turned by hand. 115

The tension of springs 55 may be regulated as desired by clamping the retaining collar in the desired position on rods 43 and then turning member 60 to obtain a fine adjustment. Since it is desirable to employ a comparatively stiff spring in order to support the heavy weights involved, the threaded outer member permits the required tension to be attained without the use of external compression means. 120

In order to shift the lamp house and apparatus equipped with springs 55, clamping 130

member 48 is loosened whereupon the weight of the rear frame and as much of the weight of the lamp house as is desirable is supported by said springs. The weight of the rear frame is thus prevented from causing rod 42 to bind in bearings 41 and in addition the operator is not required to lift the entire weight of the frame when the lamp house is shifted. Since the frame commonly weighs over 150 lbs, it is evident that this item is of considerable importance. When the lamp house is adjusted to its desired position it is clamped by tightening clamping screw 53 and lever 48 whereby further relative movement of the parts is prevented. After rods 43 have been clamped, springs 55 exert no further influence on the operation of the machine.

When it is desired to change the angle of projection, the entire apparatus is pivotally moved about pedestal 22, thereby changing the length of the rear supporting frame by causing telescoping movement thereof. If this change is greater than that provided for by springs 55, the retaining collar may be unclamped from rods 43 and the springs again adjusted after the machine has been moved to its new position. In normal operation the angle of inclination of the projection machine remains practically constant, hence adjustment as above described is only required at infrequent intervals. On the other hand, it is frequently desirable to change the position of the lamp house, as for example, for shifting from moving pictures to still pictures. It is evident, therefore, that a single adjustment of the springs 55 may be retained over a comparatively long period of time.

40 A simplified form of spring retainer is shown in Figs. 3 and 4 comprising a bar 65 provided with a circular bore at the two ends thereof for engaging rods 43. Set screws 66 may be threaded into circular ends of bar 65 to bear against rods 43 for securing the parts against relative movement. Springs 55 may be adjusted by forcing bar 65 downwardly until the desired compression has been obtained. Set screws 66 are then tightened for 50 locking the parts in the desired position.

In case it is then impractical to manually compress springs 65 by the desired amount, the result may be accomplished by raising lamp house 33 by pivoting frame about pedestal 22 thereby raising the rear bracing frame and moving rods 43 upwardly. Cross bar 65 may then be pressed against springs 55 and secured, and the entire frame again lowered, thus compressing the springs.

60 A further modified form of spring adjusting means is shown in Fig. 14. Rod 67 of that figure is shown as provided with threads 68 which are engaged by nuts 69. Spring retention member 70 engages the lower face 65 of said nuts and is provided with a recess 71

in which spring 55 is seated. Adjustment is obtained by turning nut 69 whereby retaining member 70 is forced upwardly or downwardly by the required amount.

A further construction which may be employed for facilitating the transverse movement of the lamp house and preventing the weight of the bracing frame from causing the same to bind, is shown in Figs. 11, 12 and 13 as comprising a bracket 75 secured to lamp house base 31. Said bracket is provided with downwardly extending arms 76 into which a plurality of rollers 77 are journaled. Said rollers are suitably located for engaging rod 42 and allowing lamp house to roll thereon. An intermediate split collar 78 is formed on bracket 75 and the two ends thereof are threaded to receive the clamping screw 79. The lamp house may thus be secured in its desired position by tightening screw 79 and causing split collar to firmly grip rod 42. By this construction rod 42 is prevented from binding as a result of any moment which is caused by the center of gravity of the bracing frame being offset from the center of the lamp house. Furthermore, the friction of the lamp house bracket on rod 42 is considerably reduced by the elimination of the sliding surfaces.

Machines constructed as above have been found to operate in an improved manner. The supporting springs not only serve to take the weight of the bracing frame for facilitating lateral adjustment of the lamp house, but they also operate within a limited range of movement to relieve a portion of the weight of the machine from adjusting screw 44. When springs 55 are adjusted to support a portion of the unbalanced weight of the machine in addition to that of the bracing frame, it has been found that the force required to angularly adjust the machine by means of hand wheel 39 is greatly reduced, and the operator is able to more accurately and easily control the machine. By clamping the various parts when the machine is in use, such as the extensible supporting frame, the lamp house supporting bracket, the lamp house supporting web and adjusting screw, vibrations are reduced to a minimum while the advantages of easy adjustment are still obtained.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In combination with a motion picture projection machine, a lamp house base, means for pivotally supporting said base, an adjust-

- able frame associated therewith, said frame comprising a pair of telescoping members, springs mechanically interconnecting said members, means for adjusting the tension of 5 said springs comprising a member slidably engaging one of said telescoping members, and a second member threaded thereon and having means associated therewith for seating said spring.
- 10 2. In a motion picture machine, a base, a pedestal mounted on said base, a pedestal lever pivotally carried on said pedestal and an extensible bracing frame extending between said pedestal lever and said base, said 15 base, pedestal, pedestal lever and frame forming a quadrilateral, said lever having a vertical pivot to permit lateral shifting of a lamp house, and means for supporting a portion of the weight of said frame independently of 20 said lever when said lamp house is being shifted whereby extensible movement of said frame is facilitated.
- 25 3. In a projection machine, a pedestal lever having supports thereon for a projection head and a lamp house, a pedestal supporting said lever adjacent said projection head support means for shifting said lever laterally about a vertical axis for effecting 30 lateral adjustment of said lamp house and an extensible bracing frame associated with said lever adjacent the lamp house support, and springs interconnecting the elements of 35 said extensible frame for supporting a portion of the weight thereof during adjustments of the lamp house support which involve extension of said frame.
- 40 4. In a motion picture machine, a base carrying a pedestal, a pedestal lever pivotally mounted on said pedestal, an extensible bracing frame having a pair of slidable sections 45 connected between said lever and said base and resilient means for substantially relieving the pedestal lever of the weight of one of said sections during adjustments of said machine which requires extensible movement of 50 said frame.
- 55 5. In a motion picture machine, a base carrying a pedestal, a pedestal lever pivotally mounted on said pedestal, an extensible bracing frame having a pair of slidable sections 60 connected between said lever and said base, one of said sections having a transverse rod formed as a part thereof and cooperating with the bracket secured to said pedestal and 65 adapted to slide thereon, means for clamping said bracket to said rod in any desired position and resilient means for substantially relieving said pedestal lever of the weight of one of said sections during adjustments requiring extensible movement of said frame.
- 70 6. In a motion picture machine, a base carrying a pedestal, a pedestal lever pivotally mounted on said pedestal, an extensible bracing frame having a pair of slidable sections 75 connected between said lever and said base, one of said sections having a transverse rod formed as a part thereof and cooperating with the bracket secured to said pedestal and 80 adapted to slide thereon, means for clamping said bracket to said rod in any desired position and resilient means for substantially relieving said pedestal lever of the weight of one of said sections during adjustments requiring extensible movement of said frame and means for 85 adjusting the tension of said spring members comprising a spring retaining collar adjustably secured to one of said sections.

AUGUSTO DINA.
